AUTOMATIC WAFER DIE SORTING MACHINE FOR TRANSISTORS AND INTEGRATED CIR- CUITS

David A. Glenn, Cupertino, Calif., assignor to Electro-
glas, Inc., Menlo Park, Calif., a corporation of Cali-
fornia

Filed Aug. 5, 1965, Ser. No. 86,469

Term of patent 14 years

(Cl. D55—1)

Fig. 1

F i g. 2

FIGURE 1 is a prospective view of an automatic wafer die sorting machine for transistors and integrated circuits, showing my new design.

FIGURE 2 is a side elevational view looking from the left hand side of the machine shown in FIGURE 1.

The undisclosed rear portion of the machine shown in FIGURE 1 is unornamented.

I claim:

The ornamental design for the automatic wafer die sorting machine for transistors and integrated circuits, as shown and described.
